UNITED STATES PATENT OFFICE.

ADOLPH W. MACHLET, OF ELIZABETH, NEW JERSEY.

CASE-HARDENING, &c.

1,072,134.

Specification of Letters Patent.

Patented Sept. 2, 1912.

Application filed August 17, 1908. Serial No. 446,782.

To all whom it may concern:

Be it known that I, ADOLPH W. MACHLET, a citizen of the United States, residing in Elizabeth, in the county of Union and State 5 of New Jersey, have invented certain new and useful Improvements in Case-Hardening, &c., of which the following is a specification.

This invention relates principally to case-hardening small articles, according to the improvements set forth in United States Letters Patent Nos. 822,460, 847,588, 884,180, and 884,181; although the present improvements are also of use in otherwise heating 15 or treating metal articles...

One of the principal objects of the present invention is to increase the efficiency of the apparatus and reduce the expense of case-hardening or heat-treating, and the time 20 required therefor.

Instead of stopping the machine or apparatus to discharge and recharge the same, the present improvements provide for feeding the articles automatically into the retort 25 and discharging them automatically therefrom, after they have become suitably case-hardened or otherwise acted upon.

In the preferred manner of practising the invention, a cylindrical retort of suitable 30 length is mounted in the furnace, both ends of the retort projecting from the furnace. To the receiving end of the retort is secured a drum or receiver into which the articles are fed from a lock comprising a series of 35 inclosed gates; carburizing or other gas being admitted into said drum, and said gates preventing any escape of gas during the dumping of articles into the apparatus. Said receiver drum, during its revolution, 40 discharges the articles gradually into the end of the retort, and the latter, by reason of its revolution, causes the articles to flow or creep gradually to its other end; during which time they are heated by the furnace 45 and carburized by the action of the gas. At the other end of the furnace is provided a discharge opening, which is closed by the shutter; and by means of cams, secured upon that part of the retort which extends from 50 this end of the furnace, said shutter is automatically opened once in each revolution, to discharge a few of the articles.

Other objects and advantages will herein-after appear.

In the accompanying drawings, Figure 1 is a sectional longitudinal elevation; and Fig. 2 is a plan of the case-hardening apparatus embodying the present improvements. Fig. 3 is a sectional end elevation of the same. Fig. 4 is a section taken about midway of the furnace. Fig. 5 is an end elevation of the other end of the furnace.

A metal retort 1 in the form of a long cylindrical barrel extends through a furnace 2, projecting from both ends of said furnace. The latter has burners 3 for heating the retort, as set forth in said patents. The articles are fed into the retort from a temporary receiving drum 3, which is fixed to one end of the retort; and they are discharged through an aperture 4 formed in the opposite end of the retort. A supply of gas for carburizing the articles enters through a pipe 5 provided with a valve 6; and in order to avoid escape of gas during the charging of the drum 3, I provide a lock comprising a box 7 having an upper gate 8 and a lower gate 9, each movable independently of the other by means of handles 10, 11, and each inclosed in a housing or sheath 12, Fig. 2. In charging the apparatus, the handle 10 is moved from the full line to the dotted line position to swing the gate 8 to open the box 7. Then the latter is filled with articles and the gate 8 is closed. Then the handle 11 is swung to open the gate 9, and the articles fall through the chute 13 into the drum 3. A guard 14 in the chute protects the open end of the gas supply pipe 5, which opens into said chute. A collar 15 fixed on the chute presses a packing 16 against the end of the revolute drum, to make the joint substantially gas-tight. A weight or weights 17 connected to a cord or cords 18 passing over a pulley or pulleys 19 and connected to the chute, cause the collar 15 to press the packing 16 tightly against the drum; the chute and lock being mounted upon legs 20 sufficiently yielding to permit the weights 17 to act for the stated purpose.

The drum 3 is coned, the chute 13 entering its small end. The articles accordingly descend from the chute to the large end of the drum as at 21, where they are taken up by a scoop 22 fixed in the drum. During the revolution of the drum they are carried in the scoop up above a hopper 23 secured to the head 24 with which the drum

is provided at its large end; and the articles fall from the scoop into the hopper, as at 25; and thence they descend through a hole 26 in the drum head into the end of the retort 1. It will be noticed that a tubular flange 27 cast upon the outer side of the drum head forms a socket into which the end of the cylinder is set; the two being secured by any suitable device as by bolts 28. It will also be seen that the diameter of the hole 26 in the drum head is considerably less than the diameter of the retort 1, so that a part of the drum head forms an internal brim or partial closure for the retort, to prevent the articles from dropping from the retort back into the drum when the latter has made half a revolution from the Fig. 1 position; and preferably in addition to this brim or baffle 29 is provided an apron 30 to close the upper part of the hole 26 at Fig. 1, or the lower part of said hole when the drum is turned over, to form an additional baffle to prevent escape of the articles from the retort.

25 The drum has a peripheral flange 31 which fits in grooves 32 formed on pulleys 33 suitably supported on brackets 34 erected upon the framework 35 of the apparatus. The drum is also provided with a gear consisting of a series of teeth 36 secured in a groove 37 formed in the face of the flange 31; and a pinion 38 meshes with said gear and is fixed to a drive-wheel 39 connected to any suitable source of power.

35 The retort 1, which may have considerable length to permit the articles to remain therein for any length of time before advancing to the discharge opening 4, may be supported upon rolls 39, the latter carried upon axles 40 mounted outside of the furnace upon pedestals 41, and turning in apertures 39^a formed in the furnace walls.

45 The discharge opening 4 in the retort is closed by a shutter in the form of an end disk or retort head 42 fitting within the retort about at the end of the furnace 2. A tube 43 is secured at one end of the shutter and forms an outlet for vitiated carburizing or other gas; a valve 44 being provided upon the outer end of said tube to regulate venting of the gas. The tube 43 also serves as a stem or rod, whereby the shutter or head 42 is moved to open and close the discharge aperture 4. This movement is preferably effected automatically by means of an arm or elbow 45 sliding in a guide 46 erected upon the framework, and at its upper end secured to the rod 43 by means of two collars 47 which are fixed upon the rod. At its inner end the arm is provided with a roller stud 48 to be engaged by a cam 49 secured upon an extension 50 of the retort which projects from this end of the furnace. As the retort revolves in the direction of the arrow, the cam 49 acting upon the roller stud 48 forces the arm 45 to the left together with the rod 43 and the shutter piston 42, sufficiently to close the opening 4, thus preventing the escape of the articles during the principal portion of each revolution of the retort. The cam 49 merges into a collar 51, which encircles the principal portion of the extension 50, whereby the shutter is held in its closed position until a second cam strip 52, secured upon the drum about at right angles to the cam strip 49, engages the cam stud 48 and forces it to the Fig. 1 position, thereby again opening the hole 4 for the discharge of another quantity of carburized articles, which may fall into a receptacle 53. It will be noted that the extension 50 of the retort may be supported upon rolls 54 mounted in brackets 55 secured to the head 56 of this end of the drum.

55 The receptacle 53 is preferably closed to prevent undue loss of carburizing gas from the retort, and also to prevent access of air to the heated articles. A chute 53^a is inserted into the bottom of the furnace, and leads from the retort (to which the chute is closely fitted) to a neck 53^b formed on the cover 53^c of the receptacle 53. The tubular rod 43 may be packed by a gland 57 secured to a cover or head 58, which is removably secured to the end of the retort by any suitable catches 59.

65 The retort 1 is mounted upon the rolls 39 and 54 in a manner to permit free longitudinal extension of the retort due to the heating and cooling thereof. Moreover when worn out, it may be readily removed and replaced; it being only necessary to unscrew the bolts 28 and disconnect the arm 45, when the retort may be withdrawn bodily from the apparatus and a new one substituted; the cams, head and other appurtenances being transferred to the new retort.

75 It will be understood that the drum 3 and the lock 7 may be of any suitable capacities, and that the drum may be charged while it is in revolution; so that after starting the apparatus, it is only necessary to charge the drum from time to time and remove the receptacle 53 as often as it is filled; the case-hardening operation proceeding continuously and the depth of the case hardening being practically uniform upon the articles passing through the retort, since they all remain in the retort for about the same length of time, and are equally subjected to the heat and other treatment.

85 Variations may be resorted to within the scope of the invention, and portions of the improvements may be used without others.

90 Having thus described my invention, I claim:

1. The combination with a furnace, of a retort within the furnace and projecting from an end thereof and revolvably mounted, a drum upon the projecting end of the re- 730

2. The combination with a furnace, of a retort within the furnace and projecting from an end thereof and revolvably mounted, a drum upon the projecting end of said retort to receive the articles, a scoop within the drum, and a hopper also within the drum and into which said scoop discharges, said hopper communicating with the interior of said retort. 70
3. The combination with a furnace, of a retort within the furnace, a closed revolving drum outside of the furnace to receive the articles, said drum in communication with said retort, and means within the drum to feed the articles into the retort. 75
4. The combination with a furnace, of a retort within the furnace and projecting from an end thereof, a closed revolving drum outside of the furnace to receive the articles, and provided with a scoop, inclusive of a scoop and effective upon the revolution of the drum, to feed the articles into said retort. 80
5. The combination with a furnace, of a retort within the furnace, a revolving drum to receive the articles and having means to feed them into the retort, and a lock closing said drum and including a series of gates. 85
6. The combination with a furnace, of a retort within the furnace, a revolving drum to receive the articles and having means to feed them into the retort, and a lock closing said drum and including a series of gates; means being provided for introducing into said retort a fluid to act upon the heated articles. 90
7. The combination with a furnace, of a retort revolvably mounted in the furnace, a receiver outside of the furnace and provided with a lock, means between the lock and the retort for feeding the articles from the receiver into the retort, and means to introduce into said retort a supply of gas to act upon the heated articles. 95
8. The combination with a furnace, of a retort within the furnace, a revolving drum outside of the furnace to receive the articles, said drum closed by means of a stationary lock which discharges into said revolving drum, and means within the drum to feed the articles into the retort. 100
9. The combination with a furnace, of a retort within the furnace, a revolving drum outside of the furnace to receive the articles, said drum closed by means of a stationary lock which discharges into said revolving drum, means within the drum to feed the articles into the retort, and means to introduce into said retort a supply of gas or fluid to act upon the heated articles. 105
10. The combination with a furnace, of a retort within the furnace mounted for revolution and projecting from the furnace, and a drum upon the projecting end of said retort to receive the articles, and having means, inclusive of a scoop, to feed the articles into said retort, said drum closed by means of a stationary lock provided with a series of gates and having a chute to discharge into said drum. 110
11. The combination with a furnace, of a retort within the furnace mounted for revolution and projecting from the furnace, and a drum upon the projecting end of said retort to receive the articles, and having means, inclusive of a scoop, to feed the articles into said retort, said drum closed by means of a stationary lock provided with a series of gates and having a chute to discharge into said drum; and means to introduce into said retort a supply of gas or fluid to act upon the heated articles. 115
12. The combination with a furnace, of a retort within the furnace mounted for revolution and projecting from the furnace, and a drum upon the projecting end of said retort to receive the articles, and having means, inclusive of a scoop, to feed the articles into said retort, said drum closed by means of a stationary lock provided with a series of gates and having a chute to discharge into said drum, and an inlet pipe for gas opening into said chute. 120
13. The combination with a furnace, of a revolving retort within the furnace, a receiver outside of the furnace and provided with a lock comprising a series of gates, and means to feed the articles from the receiver into the retort. 125
14. The combination with a furnace, of a revolving retort within the furnace, a receiver outside of the furnace and provided with a lock comprising a series of gates, means to revolve the retort and the receiver and means to feed the articles from the receiver into the retort; said feeding means being rendered effective by the revolution of the receiver, and said lock being stationary and having a chute to discharge into the receiver. 130
15. The combination with a furnace, of a revolving retort within the furnace, a receiver outside of the furnace and provided with a lock comprising a series of gates, means to revolve the retort and the receiver and means to feed the articles from the receiver into the retort; said feeding means being rendered effective by the revolution of the receiver, and said lock being stationary and having a chute to discharge into the receiver. 135
16. The combination with a furnace, of a revolving retort within the furnace, a receiver outside of the furnace and provided with a lock comprising a series of gates, means to feed the articles from the receiver 140

into the retort, and means being provided to supply gas to the retort.

17. The combination of a lock in the form of a box having independently operable gates, a receiver drum into which said lock discharges, rolls upon which said drum turns, a gear connected to said drum, a power-driven device engaging said gear, said drum having discharging means, a retort into which the articles are discharged from said drum, and a furnace in which said retort is mounted.

18. The combination of a lock in the form of a box having independently operable gates, a receiver drum into which said lock discharges, rolls upon which said drum turns, a gear connected to said drum, a power-driven device engaging said gear, said drum having discharging means, a retort into which the articles are discharged from said drum, and a furnace in which said retort is mounted; said retort extending from the end of said furnace and fixed to said drum, rolls on which said retort is supported for revolution, and means at the opposite end of the retort for discharging the articles therefrom; a shutter fitted in said retort and movable therealong to close and open the discharge orifice, and mechanism for reciprocating said shutter.

19. The combination of a lock in the form of a box having independently operable gates, a receiver drum into which said lock discharges, rolls upon which said drum turns, a gear connected to said drum, a power-driven device engaging said gear, said drum having discharging means, a retort into which the articles are discharged from said drum, and a furnace in which said retort is mounted; means being provided to supply a current of gas to the retort to act upon the heated articles.

20. The combination of a lock in the form of a box having independently operable gates, a receiver drum into which said lock discharges, rolls upon which said drum turns, a gear connected to said drum, a power-driven device engaging said gear, said drum having discharging means, a retort into which the articles are discharged from said drum, and a furnace in which said retort is mounted; a shutter fitted in said retort and movable therealong to close and open the discharge orifice, and mechanism for reciprocating said shutter.

21. The combination of a lock in the form of a box having independently operable gates, a receiver drum into which said lock discharges, rolls upon which said drum turns, a gear connected to said drum, a power-driven device engaging said gear, said drum having discharging means, a retort into which the articles are discharged from said drum, and a furnace in which said retort is mounted; a shutter fitted in retort and movable therealong to close and open the discharge orifice, and mechanism for reciprocating said shutter including

cams mounted upon an extension of said retort which projects from the end of said furnace.

22. The combination of a lock in the form of a box having independently operable gates, a receiver drum into which said lock discharges, rolls upon which said drum turns, a gear connected to said drum, a power-driven device engaging said gear, said drum having discharging means, a retort into which the articles are discharged from said drum, and a furnace in which said retort is mounted; said retort extending from the end of said furnace and fixed to said drum, rolls on which said retort is supported for revolution, and means at the opposite end of the retort for discharging the articles therefrom; a shutter fitted in said retort and movable therealong to close and open the discharge orifice, and mechanism for reciprocating said shutter.

23. The combination of a lock in the form of a box having independently operable inclosed gates, a receiver drum into which said box discharges, rolls upon which said drum turns, means within said drum for discharging the articles therefrom, a retort into which the articles are discharged, a furnace in which said retort is mounted, said retort extending from the end of said furnace and connected to said drum, means for discharging the articles from the retort, and means to supply a current of gas to the retort to act upon the heated articles.

24. The combination with a furnace and a revolving retort therein having a discharge opening, of a shutter for said opening, cams mounted upon an extension of the retort which projects from said furnace, and a shutter carrier operated by said cams; a cover secured upon the end of the extension, said shutter in the form of a piston or disk fitting in the cylinder and provided with a hollow stem for the passage of gas, and a gland provided in said cover for said stem.

25. The combination with a furnace and a revolving retort therein having a discharge opening, of a shutter for said opening, cams mounted upon an extension of the retort which projects from said furnace, and a shutter carrier operated by said cams; a cover secured upon the end of the extension, said shutter in the form of a piston or disk fitting in the cylinder and provided with a hollow stem for the passage of gas, and a gland provided in said cover for said stem; the latter having a regulatable vent and connected by an operating arm to said cams.

26. The combination with a furnace, and a revolving retort therein having a discharge opening, of a shutter for said opening, cams upon an extension of the retort which projects from said furnace, a cover secured upon said extension, said shutter in the form of a piston or disk fitting in the cylinder

and provided with a hollow stem for the passage of gas, a gland provided in said cover for said stem, the latter connected by an operating arm to said cams, and means for feeding articles automatically into said retort.

27. An apparatus for continuously case-hardening iron or steel articles, comprising a lock in the form of a box having upper and lower independently operable inclosed gates, a chute descending from said box, a gas supply pipe opening into said chute, a conical or tapering drum into the small end of which said chute discharges, means being provided for packing or closing the joint between the chute and the drum, the latter having a head at its large end provided with a flange, grooved rolls in which said flange fits and whereon it turns, a gear upon said flange, a power-driven pinion meshing with said gear, an interior scoop on the floor or wall of the drum at its large end, a hopper within the drum to receive the discharge from said scoop, a cylindrical retort fixed at one end to said drum head, the latter having an opening from said hopper into said retort, a baffle being provided to prevent articles from falling back from the retort into the hopper, a furnace through the walls of which said retort extends, rolls on which said retort is supported for revolution, said rolls mounted on a bar outside of the furnace and extending through the walls of the furnace to support the retort, the latter having a discharge opening at its end opposite from said hopper, a shutter fitting in said retort and movable endwise thereof to close and open said discharge opening, a detachable cover or head closing the end of the retort barrel opposite from said hopper, a tube opening through said shutter and forming an operating stem or rod therefor, said tube mounted in said retort head by means of a gland and bearing at its outer end a discharge for the spent gases, an arm supported upon the framework for a sliding movement and connected to said rod or stem to move said latter toward and from the retort, a stud upon said arm, and cams fixed upon the periphery of said extension of said retort to reciprocate said arm and cause said shutter to open and close said discharge opening, said extension being mounted upon rolls supported in brackets upon the end of the furnace.

28. The combination of a lock in the form of a box having upper and lower independently operable inclosed gates, a chute leading from said box to a receiver drum into which said chute discharges, said drum having a peripheral flange rolls upon which said flange turns, a gear upon said drum, a power-driven device engaging said gear, means within said device and including a scoop for discharging the articles therefrom,

a retort into which the articles are discharged, a furnace in which said retort is mounted, said retort extending through the end of said furnace and fixed to said drum, rolls on which said retort is supported for revolution, means at the opposite end of the retort for discharging the articles therefrom, means being provided to supply a current of gas to the retort to act upon the heated articles, a shutter fitted in said retort and movable therealong to close and open the discharge orifice, and mechanism for reciprocating said shutter, including cams mounted upon an extension of said retort projecting from the furnace, said extension being mounted upon rolls supported upon the exterior of the furnace.

29. A continuous feeding case-hardening apparatus comprising a furnace, a retort mounted therein, both ends of the retort projecting from the furnace, a drum or receiver secured to the receiving end of the retort, a lock communicating with said drum or receiver, means for supplying carburizing gas into said drum, the latter having means to feed the articles gradually into the ends of said retort, and means to revolve the retort, and cause the articles to creep to the other end of the retort, the latter being provided with a discharge opening.

30. A continuous feeding case-hardening apparatus comprising a furnace, a retort mounted therein, both ends of the retort projecting from the furnace, a drum or receiver secured to the receiving end of the retort, a lock communicating with said drum or receiver, means for supplying carburizing gas into said drum, the latter having means to feed the articles gradually into the ends of said retort, means to revolve the retort, and cause the articles to creep to the other end of the retort, the latter being provided with a discharge opening, a shutter to close said opening, and cams connected to the retort for opening and closing said shutter.

31. In a case-hardening apparatus, the combination with a retort, of a magazine fixed to one end thereof, and means to revolve the retort and magazine and cause the articles to feed from the magazine into the retort during the revolution thereof.

32. In a case-hardening apparatus, the combination with a retort, of a magazine fixed to one end thereof, the other end of the retort being provided with a discharge opening, and means to revolve the retort and magazine and cause the articles to feed from the magazine into the retort during the revolution thereof.

33. In a case-hardening apparatus, the combination with a retort, of a temporary receiving drum fixed to one end thereof, and a lock communicating with said drum

and having gates movable independently of each other.

34. A carburizing apparatus having means for automatically feeding, heating and discharging articles, said means including a retort, means for revolving said retort, a magazine connected to said retort to revolve therewith, means provided with a lock for conducting articles into said magazine, means to feed the articles gradually from the magazine into the retort, automatic discharging means at the opposite end of the retort, and means for charging the retort with carburizing gas.

15 35. The combination with a revoluble retort, and means for charging the same with carburizing gas, of an article feeder connected to said retort to revolve therewith, said retort having a discharge opening, and means connected to said retort to revolve therewith, to effect the automatic opening and closing of said discharge opening.

36. The combination with a revoluble retort, and means for charging the same with carburizing gas, of an article feeder connected to said retort to revolve therewith, said retort having a discharge opening, an internal shutter forming the end of the retort, and mechanism connected to said 30 shutter for reciprocating it during the rotation of the retort, to close and open the communication between the retort and said opening.

37. The combination with a furnace, of a retort rotatable in the furnace and having at one end a drum or magazine fixed thereto, said drum provided with a lock comprising a series of gates, whereby the drum may be charged, means for introducing gas into the 40 retort, and means dependent upon the rotation of the retort for feeding articles thereto from the drum.

38. The combination with a furnace, of a retort rotatable in the furnace and having at one end a drum or magazine fixed thereto, said drum provided with a lock comprising a series of gates, whereby the drum may be charged, means for introducing gas into the retort, means dependent upon the 50 rotation of the retort for feeding articles thereto from the drum; said retort being provided at its other end with a discharge opening, a receptacle in connection with said discharge opening, and an automatically operated shutter for said opening.

39. The combination with a furnace, of a retort rotatable in the furnace and having at one end a drum or magazine fixed thereto, said drum provided with a lock comprising 60 a series of gates, whereby the drum may be charged, means for introducing gas into the retort, means dependent upon the rotation of the retort for feeding articles thereto from the drum, said retort being provided at its other end with a discharge opening, a

receptacle in connection with said discharge opening, an automatically operated shutter for said opening; and a tube upon which said shutter is mounted; said tube serving as a vent for the retort.

70 40. An apparatus for continuously case-hardening iron or steel articles, comprising a framework, a lock in the form of a box having upper and lower independently operable inclosed gates, a chute descending from said box, a gas supply pipe opening into said chute, a conical or tapering drum into the small end of which said chute discharges, means being provided for packing or closing the joint between the chute and the drum, an interior scoop on the floor or wall of the drum at its large end, a hopper within the drum to receive the discharge from said scoop, a cylindrical retort fixed at one end of said drum head, the latter having an opening from said hopper into said retort, a furnace through the walls of which said retort extends, the latter having a discharge opening at its end opposite from said hopper, a shutter fitting in said retort and 75 movable endwise thereof to close and open said discharge opening, a detachable cover or head closing the end of the retort barrel opposite from said hopper, a tube opening through said shutter and forming an operating stem or rod therefor, said tube having at its outer end a discharge for the spent gases, an arm supported upon the framework for a sliding movement and connected to said rod or stem to move said shutter to and fro 80 in the retort, a stud upon said arm, and means to reciprocate said arm and cause said shutter to open and close said discharging opening.

85 41. The combination of a lock having independently operable inclosed gates, a receiver drum, means within said drum and including a scoop for discharging the articles therefrom, a retort into which the articles are discharged, a furnace in which said 90 retort is mounted, said retort fixed to said drum, an orifice being provided at the opposite end of the retort for discharging the articles therefrom, means being provided to supply a current of gas to the retort to act 95 upon the heated articles, a shutter fitted in said retort and movable therealong to close and open the discharge orifice, and mechanism for reciprocating said shutter.

100 42. The combination with a furnace, of a rotatable retort therein, a discharge chamber for one end of said retort, a magazine fixed to the other end of said retort, a closed lock having a gland connection to said magazine; means being provided for supplying gas to the interior of said retort, and both said magazines and said discharge 105 chamber being closed to prevent escape of gas, means dependent upon the rotation of the retort to feed the articles thereto from 110

the magazine, an opening being provided from said retort into said discharge receptacle, and means dependent upon the rotation of the retort for opening and closing 5 said opening.

43. An apparatus for continuously case-hardening iron or steel articles, comprising a lock in the form of a box having upper and lower independently operable inclosed gates, a chute descending from said box; a conical or tapering drum into the small end of which said chute discharges, an interior scoop on the floor or wall of the drum at its large end, a hopper within the drum to receive the discharge from said scoop, a retort fixed at one end to said drum head, the latter having an opening from said hopper into said retort, a furnace through the wall of which said retort extends, the latter having a discharge opening at its end opposite from said hopper, and a shutter fitting in said retort and movable endwise thereof to close and open said discharge opening.

44. An apparatus for continuously treating metal articles, comprising a lock having independently operable inclosed gates, a conical or tapering drum into which said lock discharges, an interior scoop on the floor or wall of the drum at its large end, a hopper within the drum to receive the discharge from said scoop, a retort fixed at one end to said drum head, the latter having an opening from said hopper, a furnace in which said retort is rotatably mounted, the retort having a discharge opening at its end opposite from said drum, and a shutter fitting in said retort and movable endwise thereof to close and open said discharge opening.

45. An apparatus for continuously treating metal articles, comprising a lock having independently operable inclosed gates, a conical or tapering drum into which said lock discharges, an interior scoop on the floor or wall of the drum at its large end, a hopper within the drum to receive the discharge from said scoop, a retort fixed at one end to said drum head, the latter having an opening from said hopper, a furnace in which said retort is rotatably mounted, the retort having a discharge opening at its end opposite from said drum, a shutter fitting in said retort and movable endwise thereof to close and open said discharge opening, a 55 detachable cover or head closing the end of the retort barrel opposite from said hopper, and a tube opening through said shutter and forming an operating stem or rod therefor.

46. An apparatus for continuously treating metal articles, comprising a lock having independently operable inclosed gates, a conical or tapering drum into which said lock discharges, an interior scoop on the 65 floor or wall of the drum at its large end,

a hopper within the drum to receive the discharge from said scoop, a retort fixed at one end to said drum head, the latter having an opening from said hopper, a furnace in which said retort is rotatably mounted, the 70 retort having a discharge opening at its end opposite from said drum, a shutter fitting in said retort and movable endwise thereof to close and open said discharge opening, a detachable cover or head closing the end of the retort barrel opposite from said hopper, and a tube opening through said shutter and forming an operating stem or rod therefor; said tube having at its outer end a 80 discharge for the spent gases.

47. An apparatus for continuously treating metal articles, comprising a framework, a lock having independently operable inclosed gates, a conical or tapering drum into which said lock discharges, an interior scoop on the floor or wall of the drum at its large end, a hopper within the drum to receive the discharge from said scoop, a retort fixed at one end to said drum head, the 90 latter having an opening from said hopper, a furnace in which said retort is rotatably mounted, the retort having a discharge opening at its end opposite from said drum, a shutter fitting in said retort and movable endwise thereof to close and open said discharge opening, an arm supported upon the framework for a sliding movement and connected to said shutter to move it to and fro in the retort, and means to reciprocate said arm and cause said shutter to open and close 95 said discharging opening.

48. An apparatus for continuously heat-treating iron or steel articles, comprising a closed drum or magazine, a cylindrical retort fixed at one end to said drum, the latter having an opening from said hopper into said retort, means to feed the articles from the drum into the retort, a furnace through the wall of which said retort extends, the latter having a discharge opening at its end 100 opposite from said drum, and a shutter fitting in said retort and movable to close and open said discharge opening.

49. An apparatus for continuously heat-treating iron or steel articles, comprising a closed drum or magazine, a cylindrical retort fixed at one end to said drum, the latter having an opening from said hopper into said retort, means to feed the articles from the drum into the retort, a furnace through the wall of which said retort extends, the latter having a discharge opening at its end 110 opposite from said drum, a shutter fitting in said retort and movable to close and open said discharge opening, a cover or head closing the end of the retort barrel opposite from said hopper, a tube opening through said shutter and forming an operating stem or rod therefor, said tube having at its 115 outer end a discharge for the spent gases.

50. An apparatus for continuously heat-treating iron or steel articles, comprising a framework, a closed drum or magazine, a cylindrical retort fixed at one end to said drum, the latter having an opening from said hopper into said retort, means to feed the articles from the drum into the retort, a furnace through the wall of which said retort extends, the latter having a discharge opening at its end opposite from said drum, a shutter fitting in said retort and movable to close and open said discharge opening,

an arm supported upon the framework for a sliding movement and connected to said rod or stem to move said shutter to and fro in the retort, a stud upon said arm, and means to reciprocate said arm and cause said shutter to open and close said discharging opening. 15
